UNITED STATES PATENT OFFICE.

PEMBROKE A. VAILE, OF CHICAGO, ILLINOIS, ASSIGNEE TO B. L. MACGREGOR, OF HOLLYWOOD, ILLINOIS.

GOLF CLUB.

Application filed September 24, 1927. Serial No. 221,633.

This invention relates to golf clubs, and more particularly to a "center-shafted" club.

The main object of the invention is to produce a golf club having the weight in the head so disposed relative to the shaft that the club shall be perfectly balanced laterally and shall have the main portion of the weight concentrated as nearly as possible to the center line of the force of the stroke or point of impact, and having the shaft and weight arranged so as to secure the best effect in aiming the ball toward the desired objective and in obtaining power in the stroke.

Center shafted clubs have been known for a very considerable time. In fact, nearly all modern ball playing implements are so made that the point of impact is in what may be called the striking plane of the axial line of the shaft.

In golf clubs, however, the general tendency has been to have the shaft, or handle, attached to or emanating from the heel of the club, which is that portion nearest to the player when the ball is being addressed, and to have the weight diffused laterally between the shaft and toe of the head. In such clubs there is much more torsional strain on the shaft, with a consequent alteration of the position of the face of the club at, before and after the moment of impact, than in a club such as is herein shown and described.

While some putters have been produced wherein the shaft has been centered to be approximately in line with the point of impact, golf clubs properly center-shafted and weighted to obtain perfect lateral balance, have not been heretofore produced.

On account of the fact that my improved club is perfectly balanced laterally there is far less risk of slicing and pulling, the outstanding causes of misdirection; and the arrangement of the shaft relative to the head, and of the weight relative to the shaft, tends to insure both distance and good direction.

In the drawings:

Figure 1 is an elevation showing the face of the head of the club, the shaft being broken away.

Figure 2 is a horizontal sectional view taken in the plane of the line 2—2 of Figure 3, looking in the direction indicated by arrows.

Figure 3 is a vertical sectional view taken in the line 3—3 of Figure 2.

In that embodiment of my invention which

I have chosen to illustrate in the drawings, 5 represents the head of a club and 6 the shaft. The shaft may be made of metal or wood and if made of metal may be solid or hollow. In this instance it is shown as hollow. It will, 60 of course, be understood that the shaft 6, broken away in the drawings, extends upwardly to a hand hold portion, or grip, not shown.

In a club of the type shown, namely, a driver, the head 5 is preferably made of wood, and shaped approximately as shown in the drawings. An upwardly extending portion 7 merges into the body portion of the head 5 in such relation thereto that a longitudinal bore for the shaft 6, extending centrally through said portion 7 and extending downwardly through the head 5, will terminate at the sole 8 in a position substantially opposite a vertical line drawn centrally across the flattened inclined face 9 of the head. The shaft 6 extends through this longitudinal bore and is held to the club head 5 by any well-known means as well as by the twine wrapping or whipping 10 indicated in Figure 1.

It will be understood that the form and the location of the upwardly extending portion 7 with respect to the body portion of the head 5 may be somewhat varied, depending upon the desired angle of the shaft 6 to the sole 8 of the club. In other words, in order to alter the "lie" of the club, the form and location of the portion 7 may be varied and consequently the angle of the shaft 6 altered, without departing from the scope of my invention, so long as the end of the shaft 6 terminates approximately as heretofore stated, at the sole 8, in a position approximately opposite a vertical line drawn centrally across the face 9 of the head, or so long as the shaft 6 crosses a point approximately behind or opposite the point of impact on the face.

To give the desired weight to the head of the club, it is bored and lead 11 inserted therein through an opening 12 in the back of the head. The lead 11 is preferably disposed so as to have its greatest volume, and consequently its greatest weight, toward the bottom or sole of the club, to enhance the lifting power of the club; and is arranged laterally so as to be approximately evenly disposed on each side of the inclined plane of the axis of the shaft taken on an imaginary line extending horizontally in continuation of a line 110

drawn from the center of the face 9 through the shaft 6, as indicated by the dotted line *x-x* on Figure 2; excepting that the weight of the lead toward the side 13 is greater than the side 14 to balance the greater weight of the wood 15 of the toe of the head.

The exact form of lead 11 is immaterial, but I recommend the arrangement shown in the drawings for the reason that the weight ¹⁰ is concentrated and centered about the shaft 6, mainly in rear thereof, but not necessarily in engagement therewith; and is balanced laterally with respect to the line of impact between the face of the head and the shaft, ¹⁵ and arranged vertically so as to be heavier toward the sole of the head to exert the desired lifting force upon the ball.

It will be understood that the shaft 6 may or may not extend entirely through the head ²⁰ to the sole 8. By the use of the phrase in the claims "the shaft being connected to the head so that the axis of the shaft will extend across a point approximately behind the intended point of impact on the face of the head", I ²⁵ mean that the shaft may so extend or a line in continuation of the axis of the shaft may extend in the manner stated.

I claim as my invention:

1. A golf club of the driver class comprising a head of conventional shape and a shaft, ³⁰ the shaft being connected to the head so that the axis of the shaft will extend across a point laterally of the intended point of impact on the face of the head, and a weight ³⁵ in said head disposed laterally of said shaft and in line transversely through said shaft with the point of impact on said face.

2. A golf club of the driver class comprising a head of conventional shape and a shaft, ⁴⁰ the shaft being angularly connected to the head so that the axis of the shaft will extend across a point laterally of the intended point of impact on the face of the head, and a weight in the head being disposed laterally ⁴⁵ substantially evenly on each side of the inclined plane of the axis of the shaft taken in a line extending in continuation of a horizontal line drawn from the center of the

the impact face and at an angle thereto through the shaft. ⁵⁰

3. A golf club of the driver class comprising a head of conventional shape and a shaft, the head having a flattened face, the shaft being angularly connected with the head and terminating at the sole at a point ⁵⁵ approximately opposite a vertical line drawn centrally across the face of the head, and a weight in the head being disposed laterally substantially evenly on each side of the inclined plane of the axis of the shaft taken ⁶⁰ in a line extending in continuation of a horizontal line drawn from the center of the impact face and at an angle thereto through the shaft.

4. A golf club of the driver class comprising a head of conventional shape and a shaft, ⁶⁵ the shaft being connected to the head so that the axis of the shaft will extend across a point laterally of the intended point of impact on the face of the head, a metallic weight ⁷⁰ heavier in its lower than at its upper portion, arranged in the head so as to be substantially evenly disposed on each side of the inclined plane of the axis of the shaft taken ⁷⁵ in a line extending in continuation of a horizontal line drawn from the center of the impact face and at an angle thereto through the shaft.

5. A golf club of the driver class comprising a head of conventional shape and a shaft, ⁸⁰ the shaft being connected with the head and terminating at the sole at a point approximately opposite a vertical line drawn centrally across the face of the head, a metallic weight heavier in its lower than at its upper ⁸⁵ portion, arranged in the head so as to be substantially evenly disposed on each side of the inclined plane of the axis of the shaft taken ⁹⁰ in a line extending in continuation of a horizontal line drawn from the center of the impact face and at an angle thereto through the shaft.

In testimony, that I claim the foregoing as my invention I affix my signature, this 22d day of September, 1927.

PEMBROKE A. VAILE.
